US00D523413S

(12) **United States Design Patent** (10) **Patent No.:** **US D523,413 S**
Dayan (45) **Date of Patent:** **** Jun. 20, 2006**

(54) **MODULATOR**

(75) Inventor: **Mervin A. Dayan**, Oakhurst, NJ (US)

(73) Assignee: **Intellectual Solutions, Inc.**, Eatontown, NJ (US)

(**) Term: **14 Years**

(21) Appl. No.: **29/233,604**

(22) Filed: **Jul. 7, 2005**

(51) **LOC (8) Cl.** **14-03**

(52) **U.S. Cl.** **D14/155**

(58) **Field of Classification Search** D21/566; D14/299, 240, 188, 162, 155, 137; D13/168, D13/144, 110, 107; D10/106; 439/668, 490, 439/348, 32; 361/730

See application file for complete search history.

(57) **CLAIM**

The ornamental design for a modulator, as shown and described.

DESCRIPTION

FIG. 1 is a perspective view of a modulator showing my design.

FIG. 2 is a right-side view of the modulator of FIG. 1.

FIG. 3 is a left-side view of the modulator of FIG. 1.

FIG. 4 is a front view of the modulator of FIG. 1.

FIG. 5 is a rear view of the modulator of FIG. 1.

FIG. 6 is a top view of the modulator of FIG. 1.

FIG. 7 is a bottom view of the modulator of FIG. 1.

FIG. 8 is an articulated view of the right-side of the modulator of FIG. 1.

FIG. 9 is another articulated view of the right-side of the modulator of FIG. 1.

FIG. 10 is another articulated view of the right-side of the modulator of FIG. 1.

FIG. 11 is another articulated view of the right-side of the modulator of FIG. 1.

FIG. 12 is another articulated view of the right-side of the modulator of FIG. 1; and,

FIG. 13 is another articulated view of the right-side of the modulator of FIG. 1.
